UNITED STATES PATENT OFFICE

ELIAS L. CRISS, OF FARMINGTON, WEST VIRGINIA

ANTITRACK SPREADER

Application filed November 20, 1928. Serial No. 320,662.

The present invention relates to a device on which railroad tracks may be mounted to prevent the spreading of the rails and the objects and advantages of the invention will 5 appear as the description proceeds when taken in conjunction with the accompanying drawings, wherein:

Figure 1 is a top plan view of the track,

Figure 2 is a transverse section there- 10 through,

Figure 3 is a perspective view of one mem- 15 ber of one of the devices,

Figure 4 is a perspective view of the other member,

Figure 5 is a fragmentary transverse section 20 through the track being taken through one rail only showing the members about to be assembled, and

Figure 6 is a detail section taken substan- 25 tially on the line 6-6 of Figure 2.

Referring to the drawing in detail it will be seen that numerals 5 denote a pair of conventional rails. A plurality of my improved devices may be used for supporting these rails 25 and each device includes a pair of members.

Each member comprises an elongated body having one end relatively wide as is indicated at 6 and the remaining portion relatively narrow as indicated at 7. The extremity of the 30 relatively narrow portion has a notch 8 therein. The extremity of the relatively wide end portion 6 is provided with a notch 9 adjacent the portion 7.

The portion 7 immediately adjacent the 35 end 6 is cut out to provide a rail seat 10. In assembling the device the members are placed under the rails so that the portions 7 are disposed alongside of each other and then one member is driven so that the flange of one 40 rail fits into the notch 9 and then the other member is driven so that said flange is received in the notch 8 thereof.

Obviously when the flange of one rail is in the notch 9 of one member the flange of 45 the other rail is in the notch 8 of the same member.

When the members have been slid from the position shown in Figure 5 to the position shown in Figure 2 they are bolted together 50 by a plurality of bolts 12 and it is preferable

to provide the portion 7 with apertures 14 that come into registry when the members are in proper engagement with the rails.

Thus these devices not only function as ties for supporting the rails but absolutely 55 prevent the rails from spreading or tilting.

It will be seen that the rails cannot be pushed out at the bottom nor can the rails be tilted as this device is so constructed as to brace both the top and bottom of the rails. 60

It will further be seen that this device is exceedingly simple in its construction and may be manufactured at a low cost and yet be constructed strong and durable to readily withstand the elements. Furthermore it will 65 be seen that the device is easy to assemble and is thoroughly efficient and reliable in use.

It is thought that the construction, utility and advantages of this invention will now be quite apparent to those skilled in the art 70 without a more detailed description thereof.

The present embodiment of the invention has been disclosed in considerable detail merely for the purposes of exemplification since in actual practice it attains the features 75 of advantage enumerated as desirable in the statement of the invention and the above description.

It will be apparent that changes in the details of construction, and in the combination 80 and arrangement of parts may be resorted to without departing from the spirit or scope of the invention as hereinafter claimed or sacrificing any of its advantages.

Having thus described my invention, what 85 I claim as new is:

An anti-track spreading device comprising a pair of like companion members of equal length and height, having their upper faces cut away adjacent to the opposite ends to 90 provide rail seats, said ends being enlarged laterally and having the inner faces thereof notched for reception of a rail flange, the opposite ends of said members being notched 95 for engaging the companion rail flanges and said ends being adapted to abut portions of said lateral enlargements, and means holding 100 said members together.

In testimony whereof I affix my signature.

ELIAS L. CRISS.
